Robert H. Wright

Attorney

UNITED STATES PATENT OFFICE.

GEORGE HALINKA, OF DETROIT, MICHIGAN.

LOCK.

1,299,177.

Specification of Letters Patent.

Patented Apr. 1, 1919.

Application filed September 14, 1918. Serial No. 254,067.

To all whom it may concern:

Be it known that I, GEORGE HALINKA, a citizen of the United States of America, residing at Detroit, in the county of Wayne

5 and State of Michigan, have invented certain new and useful Improvements in Locks, of which the following is a specification, reference being had therein to the accompanying drawings.

10 This invention relates to locks, and the object of my invention is to provide a lock embodying a latch bar, a handle for moving the latch bar to a retracted position, and a permutation mechanism adapted to 15 prevent the retraction of the latch bar, unless the permutation mechanism is properly set.

The lock may be used in various places, but more particularly on the door of an automobile or other vehicle, since the handle 20 of the lock is countersunk in the lock casing and does not present a protuberance relative to the door. The handle is shaped that it may be easily gripped by the fingers to actuate the latch bar of the lock, and all the 25 mechanism is compactly assembled and may be easily maintained in an operatable condition.

My invention will be hereinafter specifically described and then claimed, and reference will now be had to the drawings, 30 wherein—

Figure 1 is a longitudinal sectional view of the lock; and

Fig. 2 is a front elevation of the same. 35 In the drawing, the reference numeral 1 denotes, by the way of an example, a portion of a door that is recessed, as at 2, to provide clearance for the lock, which comprises an angle plate 3 adapted to be connected to the 40 door 1 by screw bolts 4 or other fastening means.

Supported at one end of the angle plate 3 is a conventional form of permutation mechanism 5 including rotatable disks 6 disposed 45 in parallelism and provided with notches 7.

At the opposite end of the plate 3 is a latch bar 8 having a head 9, a yoke 10, and a latch 11. The latch bar 8 is slidable in bearings 12, carried by a handle casing 13 supported by and inset relative to the angle 50 plate 3.

In the handle casing 13 is a stirrup shaped handle 14 provided with a finger piece 15,

said casing providing clearance for the fingers so that the finger piece 15 may be 55 gripped to swing the handle out of the casing 13.

One end of the handle 14 has a lug 16 extending into the recess 2 of the door 1, and also into the yoke 10 of the latch bar 8, said 60 lug being pivotally held on a pin 17 mounted in apertured lugs 18 carried by the angle plate 3. It is therefore possible to swing the handle 14 outwardly, from the handle casing 13 and cause the lug 16 to retract the latch 65 bar 8. To hold the latch bar in an extended position, a coiled compression spring 19 encircles said bar between the yoke 10 and one of the bearings 12.

When the disks 6 of the permutation 70 mechanism are properly adjusted to place the notches 7 in alinement, then the head 9 of the latch bar 8 may enter said notches, when the latch bar is retracted by swinging the 75 handle 14 out of the casing 13. When the notches 7 of the disks 6 do not aline, then the head 9 of the latch bar 8 will impinge against the peripheries of the disks 6 and prevent the retraction of the latch bar 8 by the finger piece or handle of the lock. 80

What I claim is:—

The combination with an angle plate and a permutation mechanism at one end thereof, of a handle casing carried by said plate intermediate the ends thereof, bearings on the inner face of said handle casing, a latch bar 85 slidable in said bearings and having one end thereof at said permutation mechanism and the movement of said bar controlled in a radial direction thereby, a yoke at the opposite end of said bar, a stirrup shaped handle pivotally supported by said angle plate with said handle normally in said handle casing and adapted to be swung outwardly 90 away from said permutation mechanism, and a lug carried by the pivoted end of said handle engaging in the yoke of said latch bar and adapted to shift said bar toward 95 said permutation mechanism.

In testimony whereof I affix my signature 100 in the presence of two witnesses.

GEORGE HALINKA.

Witnesses:

KARL H. BUTLER,
ANNA M. DORR.
